CLAIM

The ornamental design for the wheelchair castor posts, as shown and described.

DESCRIPTION

FIG. 1 is a rear perspective view of the wheelchair castor posts of the present invention;

FIG. 2 is a front perspective view of the wheelchair castor posts of FIG. 1;

FIG. 3 is an enlarged front perspective view of the wheelchair castor posts of FIG. 1 shown with most of the unclaimed environment (dashed lines) removed for better clarity;

FIG. 4 is a front elevation view of the wheelchair castor posts of FIG. 3;

FIG. 5 is a right side elevation view of the wheelchair castor posts of FIG. 3, which is substantially a mirror image of the left side elevation view of the wheelchair castor posts;

FIG. 6 is a rear elevation view of the wheelchair castor posts of FIG. 3; and,

FIG. 7 is a plan view of the wheelchair castor posts of FIG. 3. The dashed broken lines illustrate the environment of the designs, while the dot-dash broken lines represent boundary lines of the designs. None of the broken lines form any part of the claimed design.

1 Claim, 6 Drawing Sheets
